UNITED STATES PATENT OFFICE.

J. CARL AND JAMES W. HEATH, OF GRENADA, MISSISSIPPI.

IMPROVEMENT IN CASTING SCREW-AUGERS.

Specification forming part of Letters Patent No. 29,668, dated August 21, 1860.

To all whom it may concern:

Be it known that we, JONATHAN CARL and JAMES W. HEATH, both of Grenada, in the county of Yalabusha and State of Mississippi, have invented a new and useful Improvement in Casting Spiral Augers; and we hereby declare the following to be a full, clear, and exact description thereof, reference being had to the accompanying drawings, making part of this specification.

Our said invention is chiefly designed to facilitate the construction of augers adapted for boring earth and analogous uses.

Its novelty consists in a peculiar construction and combination of patterns, and in the mode of their application to form the molds, as will be hereinafter fully explained.

In the accompanying drawings, Figure 1 represents a plan of the nowel inverted, showing the follow-board with patterns in position thereon ready for the packing. Fig. 2 is a top view of the same with the follow-board removed and the patterns ready for drawing. Fig. 3 is a plan of the cope in its inverted position when packed with sand, the shaft being removed and the spirals ready for drawing.

B represents the nowel or lower part of the flask, and F, Fig. 1, the face of the follow-board.

A is a semi-cylindrical pattern for one-half of the shaft. The said pattern is fixed in position on the follow-board with its flat side down, as exhibited in Fig. 1.

H are patterns of the spiral blades, formed in segments of ninety or one hundred and eighty degrees, and tapering in thickness from a sixteenth to an eighth of an inch to facilitate drawing. The said segments are fixed in position on the follow-board over the shaft-pattern A, the said board and the convex surface of the shaft-patterns being previously marked therefor, as seen at f in Fig. 1.

C, Fig. 3, represents the under side of the cope.

H' are segmental patterns, forming, in connection with the patterns H, complete spirals.

c represents a semi-cylindrical cavity in the packing of the cope, from whence a pattern

the counterpart of A has been drawn, as hereinafter explained.

h are studs which are screwed into the thicker edge of each spiral pattern, to draw the same, as will be hereinafter explained.

The patterns above described and represented are formed of any suitable material, and in number and size sufficient to construct an auger of the desired dimensions.

The operation is as follows: The half-shaft pattern A is placed in position on the follow-board, as shown in Fig. 1, and secured thereto with dowels or otherwise. The correct positions for the spiral segments are then marked upon the follow-board and shaft, as seen at f in Fig. 1, and the patterns H doweled or otherwise secured thereto. The nowel is then rammed with sand and turned to an upright position and the follow-board removed. This stage of the operation is represented in Fig. 2. A precise counterpart of the semi-cylindrical pattern A is then placed upon the latter with the flat side down, and secured thereto with dowels or otherwise, forming a complete shaft. The spiral segments H' are then placed, with dowels or otherwise, upon their mates H, so as to form in connection therewith complete spirals. The cope is then placed in position and rammed with sand, gates and channels being provided in either form represented. The flask is then parted and each half shaft drawn, and the spiral segments H and H' each drawn separately, turning upon their axes in the direction of the thicker edge until clear of the sand. Segments of ninety degrees are drawn in a precisely similar manner, excepting that they are drawn from the center each way, the thick edge of each having been placed uppermost, while the thin edges meet below. The flask is then closed together, a wrought-iron shaft being used, if desired, to which the spirals will be attached in casting; otherwise the space is left (either with or without a core) to form, in connection with the spirals, a hollow or a solid cast-metal shaft, as may be preferred.

The metal may be introduced through a spray from a single pouring-hole, as seen at f,

or through a separate gate for every segment, as represented at *g*.

We claim as new and of our invention herein and desire to secure by Letters Patent—

The combination of the shaft-pattern *A* and the segmental spirals *H* and *H'*, constructed, arranged, and applied in the manner set forth, for the formation of molds for casting spiral augers.

In testimony of which invention we hereunto set our hands.

J. CARL.
J. W. HEATH.
